H. THAYER.

CROW JACK.

APPLICATION FILED JAN. 19, 1914.

1,111,195.

Patented Sept. 22, 1914.

UNITED STATES PATENT OFFICE.

HARRY THAYER, OF SIDNEY, MAINE.

CROW-JACK.

1,111,195.

Specification of Letters Patent. Patented Sept. 22, 1914.

Application filed January 19, 1914. Serial No. 813,144.

To all whom it may concern:

Be it known that I, HARRY THAYER, a citizen of the United States, residing at Sidney, in the county of Kennebec and State of Maine, have invented a new and useful Crow-Jack, of which the following is a specification.

This invention relates to improvements in crow-jacks.

10 The object of the present invention is to provide a crow jack which will simulate to a certain extent the movements of a human being and will present the external appearance thereof so as to scare or frighten crows or other birds.

20 A further object is to provide a device which will present the appearance of a human being and will be provided with paddles located at the extremities of outstretched arms and which will be rotated by the wind and which are connected by a shaft, which latter is designed to oscillate the head.

25 A further object is to provide a crowjack pivotally secured upon an upright which extends along one leg and with the other leg extended and acting in the capacity of a vane to hold the jack in certain and definite relation with reference to the wind so that 30 the paddles located at the extremities of the arms will be rotated with the result hereinbefore referred to.

35 With the foregoing and other objects in view which will appear as the description proceeds, the invention resides in the combination and arrangement of parts and in the details of construction hereinafter described and claimed, it being understood that changes in the precise embodiment of the 40 invention herein disclosed, can be made within the scope of what is claimed, without departing from the spirit of the invention.

45 In the drawings accompanying this specification and forming a part thereof, the preferred embodiment of my invention is illustrated, in which:

50 Figure 1 is a view in perspective of my improved crowjack. Fig. 2 is a similar view in which the clothing has been removed in order to illustrate the working features thereof. Fig. 3 is a detail view of the head operating or oscillating mechanism.

Referring to the drawings in which similar reference numerals designate corresponding parts throughout the several views, 4 represents a base or supporting structure to which is rigidly secured the vertically extending rod 5 upon which my improved crow jack is pivotally mounted. In 55 this connection it is to be noted however, that the exact mounting may vary as local conditions and circumstances may warrant. Pivotally or rotatably mounted upon the rod 5 is the frame which includes the post 6 60 which is provided with the bearings 7 whereby it is held in a vertical manner. Rigidly secured to the post 6 and adjacent the upper extremity is the cross bar 8 along which extends the horizontal shaft 9. The 70 cross bar 8 is provided with the bearings 10 which revolvably support the shaft 9 and to which shaft at its extremities are secured the blade carrying bosses 11. A single blade 75 is secured to each of the blade carrying bosses and project in opposite directions and are adapted to be rotated by the force of the wind when blowing in a direction parallel to the longitudinal axis of the shaft 9. The bracket 12 is rigidly secured to the cross bar 80 8 and is bifurcated at its upper front extremity as at 13 and between the projecting prongs of which is pivotally secured the lever 14 which carries at its upper extremity the head-like block 15. Thus the head-like 85 block is adapted to pivot about the end of the bracket 12 and when so oscillating, taken in connection with the waving of the blades will simulate the motions of a human being to such an extent as to scare or frighten 90 animals which may be in the immediate neighborhood. The shaft 9 is provided with the cam 16 which is rigidly secured thereto and the periphery of which contacts with and is adapted to move the lever 14. 95 In order to insure that the lever will remain at all times in contact with the peripheral surface of the cam, a spring member 17 is provided and is rigidly fixed to the frame. The spring arm 17 also performs the desirable 100 function of holding the clothing of the device out of contact with the cam and the lever so that there will be no likelihood of the clothing becoming entangled in the moving parts.

In order to make the device present the

appearance of a person, the outstanding leg 18 is provided rigidly secured to and forming a part of the frame and it also performs the desirable feature of acting as a vane 5 keeping the paddles 19 in the wind. The leg 18 forms a part of or may be rigidly secured to the cross bar 8. In order to strengthen the entire structure, a cross strut 20 is provided secured to the post 6 and leg 10 18 and also to a second fragmental post 6' which is spaced in such manner that the spring 17 will come centrally between the posts 6 and 6'.

The lower extremities of the post 6 and 15 leg 18 are shaped to illustrate a foot so as to maintain the representation of a person. In order for the device to further simulate the appearance of a human being, a pair of trousers 21 are placed upon the post 6 and 20 leg 18, it being noted that the same may be accomplished by raising the post 6 so that the bearing 7 will disengage and be removed from the upright vertical rod 5 or the same may be accomplished by splitting one of the 25 trouser legs and securely nailing the same to the post. A coat 22 is also buttoned around the central portion of the frame and is held from collapsing by the posts 6 and 6' and the sleeves of the coat extend out over 30 the extremities of the cross bar 8. In order that the coat may be secured to the crow jack, one of the sleeves is slit and the coat sleeve then securely held to the jack by nails or other suitable means. It is to be noted 35 that the paddle receiving bosses 11 may be removed in order to assemble the coat upon the frame. Thus as illustrated in Fig. 1, with a hat 23 to complete the make-up, the device will present all the appearances of a 40 human being. The spring 17 will prevent the coat from becoming entangled in or interfering with the operation of the lever 14. The outstanding leg 18 will, as stated, hold the device in proper relation to the wind and 45 with the result that the paddles 19 will rotate the shaft 9 and oscillate the head-like block 15 back and forward and which motions will be sufficient to frighten animals which may be in the immediate vicinity. 50 The device is to be placed in corn fields or other places which are to be protected against the ravages of birds or animals.

A further feature is by the providing of 55 a single blade outstanding from each boss 11 and by extending the two paddles in opposite directions, an oscillatory motion will be imparted to the figure about a vertical axis due to the varying and uneven centrifugal forces and unbalanced effect of the rotation 60 of the paddles. Thus the figure will tend to oscillate about the vertical axis through limited arcs and which combined with the aforementioned motions provides for an efficient working of the device.

Having thus fully described my invention, 65 what I claim is:—

1. A device of the class described comprising a frame, means for pivotally supporting the same to rotate about a vertical axis, a cross bar carried by said frame, a shaft rotatably carried by said cross bar and provided with oppositely extending wind operated blades at its extremities extending in opposite directions, and a head-like block pivotally mounted upon said frame, and means carried by said head block and shaft adapted to oscillate the former by and with the latter.

2. A crow jack comprising a supporting base, a frame rotatably carried thereby and adapted to rotate about a vertical axis, said frame including a horizontally extending cross bar, a shaft rotatably carried by said cross bar and extending substantially horizontal, paddle blades carried at the extremities of said shaft and adapted to be actuated by the wind, a cam carried by said shaft, a head pivotally secured to the said frame and with a portion thereof extending in the path of motion of the said cam and adapted to be oscillated thereby, and means for holding the said portion of the head block in contact with the peripheral surface of said cam.

3. A crow jack comprising a frame including a pivoted head adapted to imitate the appearance of a human figure, means for mounting the same to rotate about a vertical axis, and wind operated means carried by the said figure adapted to oscillate the said head.

4. A crow jack comprising a frame including a movable head adapted to imitate the appearance of a human figure, means for mounting the same to rotate about a vertical axis, and wind operated paddle blades carried at the extremities of the arms of the figure and adapted to oscillate the head thereof.

5. A crow jack comprising a supporting base, a frame imitating the legs, body portion, arms and head of a human figure, said frame rotatably secured to the base and adapted to rotate about a vertical axis, a shaft extending along the arms of the said frame and provided with oppositely extending wind actuated paddles at the extremities thereof, the said head pivotally secured to the said frame and adapted to oscillate about a horizontal axis, and means carried by the said shaft adapted to oscillate the head during the rotation thereof, and the said frame provided with one of the legs extended, said extended leg adapted to act as a vane holding the paddle blades in the required position with respect to the direction of movement of the wind.

6. A crowjack comprising a supporting base, a frame including outstanding legs and

arms, a shaft extending along one of said legs and rotatably mounting the said frame to swing about a vertical axis, the other of said legs forming a vane for the positioning of the frame in a definite position to the wind, and paddle blades rotatably carried by the arms and held in operable relation to the wind by said leg.

In testimony that I claim the foregoing as my own, I have hereto affixed my signature in the presence of two witnesses.

HARRY THAYER.
